UNITED STATES PATENT OFFICE.

LEON F. N. BALDWIN, OF EDGEWOOD, RHODE ISLAND, ASSIGNOR OF ONE-HALF TO
BENJAMIN S. CLARK, OF PROVIDENCE, RHODE ISLAND.

CROSSWALK MARKER.

Application filed May 1, 1926. Serial No. 106,107.

This invention relates to a traffic indicating crosswalk marker; and has for its object to provide a plate adapted to be set into the sidewalk, carrying traffic directions on its face.

A further object of this invention is to provide means for illuminating the plate so as to attract the attention of the traffic.

With these and other objects in view, the invention consists of certain novel features of construction, as will be more fully described, and particularly pointed out in the appended claims.

In the accompanying drawings:

15 Figure 1 is a perspective view illustrating my improved plate as set into the face of the sidewalk to indicate the crossing place.

20 Figure 2 is a plan view of the traffic directing plate showing the markings thereon to be read from both sides of the plates.

25 Figure 3 is a section on line 3—3 of Figure 2 showing the edges as arranged to be dovetailed and so fastened into the face of the sidewalk.

30 Figure 4 is a sectional side elevation illustrating my improved traffic directing plate as inserted into the sidewalk and showing pockets at its end carrying lamps to illuminate portions of the plate.

Figure 5 is a view of the pocket covering lens locking ring.

It is found to be of advantage in city streets where traffic is heavy to set a plate in the sidewalk to indicate to the pedestrians where they are to cross the street and also to indicate to the vehicular traffic in the street where the cross walks are, so that they will not stop thereon to block the same.

It is also found to be of advantage to illuminate these traffic directing plates so as to call attention thereto, and the following is a detailed description of the present embodiment of my invention and showing one construction of traffic directing plate by which these advantageous results may be accomplished:—

With reference to the drawings, 10 designates my improved traffic directing plate which is preferably provided with beveled

side edges 11 and which are herein shown as being formed with circular end portions 12, which are provided with hollow protuberances 13 on their under sides, each forming a pocket 14 for the reception of an illuminating lamp 15 by which attention is attracted to the plate.

A lens 16 is placed or set into each pocket to rest upon a rubber packing 17 about its edge and a lock ring 18 is employed to bind the lens against the packing to make the pockets water tight.

In practice I preferably set the plate into the surface of the walk and flow cement or other material of which the walk is constructed over the inclined edges thereof to lock the plate firmly into the face of the walk, which, in most instances, is sufficient to securely retain the plate in position without bolts or other locking means. On the face of this plate, I preferably form traffic-directing indications so that a pedestrian approaching along the sidewalk can read the sign "Cross here" while vehicular traffic in the road will see on the opposite side of the same plate the words "Cross walk", which will indicate to them that they must not stop and block this walk.

In some instances instead of positioning an electric lamp in this pocket 14, I may cover the face of the pocket with illuminating material so that it will shine through the lenses and attract the attention of traffic.

My improved traffic direction cross walk marker is very practical in construction and is effective in its operation showing to both pedestrians and vehicular traffic the position of the crossings.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. A traffic directing crosswalk marker comprising an elongated plate to be set into the sidewalk and carrying traffic directions thereon said plate having a pocket formed

therein for the reception of an illuminating member and a lens closing the pocket opening and covering said member.

2. A traffic directing cross walk marker comprising an elongated plate having a lamp receiving pocket formed at each end thereof, and a lens for closing the pocket.

3. A traffic directing cross walk marker

comprising an elongated plate having hollow protuberances forming lamp receiving pockets at its ends to be set into the side walk, the face of the plates having traffic directions thereon. 10

In testimony whereof I affix my signature.

LEON F. N. BALDWIN.
